UNITED STATES PATENT OFFICE

CHARLES A. PIERSON, OF TOLEDO, OHIO, ASSIGNOR TO THE STANDARD ELECTRIC STOVE
CO., OF TOLEDO, OHIO, A CORPORATION OF OHIO

DESIGN FOR AN ELECTRIC COOK STOVE

Application filed April 14, 1932. Serial No. 43,491. Term of patent 7 years.

To all whom it may concern:

Be it known that I, CHARLES A. PIERSON, a citizen of the United States, and a resident of Toledo, Lucas County, Ohio, have invented a new, original, and ornamental Design for an Electric Cook Stove, of which the following is a specification, reference being had to the accompanying drawing, forming a part thereof.

In the drawing, Fig. 1 is a perspective view

of an electric cook stove embodying the invention, and Fig. 2 is a similar view partly open.

I claim:

The ornamental design for an electric cook stove, substantially as shown.

In testimony whereof I have hereunto signed my name to this specification.

CHARLES A. PIERSON.
